HAND GRENADE

Filed Jan. 21, 1946

FIG. 1

FIG. 3

FIG. 5

FIG. 4

Inventor:
T. Petersen,
By E. F. Olander, Atty

position, the free ends of the loop engage in recesses 31 and 32, respectively, in the edge of the lugs 15 and 16, respectively, as best illustrated in Figs. 1 and 4.

The loop is released by swinging it in the direction of the arrow A in Fig. 1 from the position shown in full lines in Figs. 1, 2 and 3 to the position shown in dot and dash lines in Fig. 1, in which released position of the loop the lever 21, 22 may swing from the position shown in Fig. 1 to that shown in Fig. 4. The loop is resiliently expandible, and each of the shoulders 29, 30 is provided with an inclined surface 33 to produce a resilient expansion of the loop during the beginning of the swinging of the same from the safety position, so that the loop is resiliently held in the safety position by its own spring action.

During the swinging movement of the lever 21, 22 towards the position shown in Fig. 4, the ends 25, 26 of the released loop describe an arc the centre of which is situated on the axis of the pivot pins 19, 20. The upper parts of the edges of the recesses 31, 32 should therefore have a shape corresponding to the said arc, as indicated in Fig. 4, in order that the loop shall not get stuck in the recess 31, 32, whereby it would prevent the said swinging movement of the lever 21, 22.

In order that the loop may be returned from the released position shown by dash and dot lines in Fig. 1 to the safety position shown by full lines in Figs. 1, 2 and 3, each of the shoulders 29, 30 should further be provided with a second inclined surface 34 to facilitate the expansion of the loop necessary for bringing it in the safety position.

In order that the loop may be returned by a single motion from the released position to the safety position one condition is, of course, that the free ends of the loop do not slide along the lever arm 22 when the loop is in the released position. Such sliding would occur if the recesses 31 and 32 were relatively shallow and the lever arm 22 were allowed to swing out somewhat from the grenade body. In order to prevent such sliding, the longitudinal edges of the lever arm 22 may be provided with recesses 35 as shown in Fig. 5, to form suitable abutments for the free ends 25, 26 of the loop.

It should be mentioned for the sake of completeness that in the embodiment shown in Fig. 5 the spring eye 24 comprises two coils as distinguished from the embodiment shown in Figs. 1, 2, 3 and 4 in which the spring eye comprises but a single coil.

The hand grenade should further be provided with a carriage safety means. For this purpose it is advantageous to use a cotter pin 36, which is provided with a loop-shaped handle and is inserted in holes in the lugs 15, 16 and the striker 9 at a point situated slightly above a plane through the two branches 27, 28 of the loop, when the latter is in the safety position, whereby the striker is locked in its cocked position by the cotter pin 36.

The handling and operation of the hand grenade will be apparent from the following.

When hand grenades are distributed to the fighting forces, the carriage safety pin 36, the fight safety loop 24 to 28 and the throw safety lever 21, 22 are in the position shown in Figs. 1, 2 and 3. When fighting is expected to be imminent, the soldier removes the cotter pin 36. When the fighting has begun and the soldier is about to throw a hand grenade, he shall take hold of the grenade in such a way that by the index, middle, ring and little fingers of the

throwing hand the lever arm 22 is held securely against the grenade body and the thumb of the throwing hand can press the loop 24 to 28 upwardly over the shoulders 29 and 30 to the position shown by dash and dot lines in Fig. 1. During the preparation of the throw, the striker of the grenade is blocked, if the thrower holds the lever arm 22 securely against or almost against the grenade body, for the lever arm 21 will then retain the striker 9 in the cocked position against its spring 10. When the throw has been carried out and the hand grenade has left the throwing hand of the thrower, the lever 21, 22 swings under the action of the spring 10 about the pivots 19 and 20, so that the striker 9 is released and forced by the spring 10 against the cap (not shown) on the nipple 13 so as to ignite the fuse.

In the hand grenade according to the invention, the fight safety member 24 to 28 may be released, as shown, by means of the throwing hand, which is not possible in the previously known hand grenades, where both hands must be used for releasing the fight safety means. In addition, the hand grenade according to the invention provides the following advantages.

If, after release of the fight safety member, for some reason or other the thrower does not want to throw the hand grenade, he may render the hand grenade safe by pressing, with the thumb of the throwing hand or in any other manner, the end 24 of the loop against his own body, the ground or any other suitable object so as to return the loop 24 to 28 over the shoulders 29, 30 to the safety position.

After the fight safety member 24 to 28 has been returned to the safety position, the cotter pin 36 serving as a carriage safety means may easily be replaced.

The invention is not limited to the embodiment shown and described by way of example above and in the drawings, but may be varied in several different manners within the scope defined by the accompanying claims.

What I claim and desire to secure by Letters Patent is:

1. A hand grenade of the character described, comprising, in combination, a grenade body having an opening, a head screwed into said opening and having, on top of it, two spaced approximately semi-circular lugs, a spring-pressed striker mounted in said head and having a notched end projecting into the space between said lugs, a throw safety lever which has pivot pins received in notches provided in the edges of said lugs, and which, when in its safety position, has one end engaged with the projecting notched end of the striker to hold the latter in cocked position against its spring, and a fight safety member in the form of a resiliently expandible, approximately rectangular, wire loop which, when in its safety position, embraces the projecting lugs adjacent their base and holds the throw safety lever in its safety position, and which has the ends of the wire at one end of the rectangle engaged with the throw safety lever, the wire being formed into a coil at the other end of the rectangle, so that the loop may be swung upwardly around the first end of the rectangle out of its safety position by pressing said coil upwardly by the thumb of the throwing hand, and returned to its safety position by pressing the coil in the opposite direction.

2. A hand grenade as claimed in claim 1, in which the edges of the lugs are provided with notches for the wire of the approximately rec-

tangular loop at the end thereof engaged with the throw safety lever.

3. A hand grenade of the character described, comprising, in combination, a grenade body having an opening, a head screwed into said opening and having, on top of it, two spaced approximately semi-circular projecting lugs, said lugs having double inclined surfaces thereon converging to a high point intermediate the top and bottom of said lugs, a spring-pressed striker mounted in said head and having a notched end projecting into the spaces between said lugs, a throw safety lever pivoted on said lugs and, when in its safety position, having one end engaged with the notched end of the striker to hold the latter in cocked position against its spring and a fight safety member in the form of a resiliently expansible, approximately rectangular wire loop swingably secured at one end thereof to said throw safety lever and which, when in its safety position, embraces the projecting lugs on the head of the grenade and holds the throw safety lever in its safety position, the other end of said fight safety member being closed and adapted to abut the said head at the side opposite from said

throw safety lever, said loop being swingable about said throw safety lever out of its safety position by the thumb of the throwing hand.

4. A hand grenade as claimed in claim 3, in which a withdrawable carriage safety pin penetrating the lugs and the projecting end of the striker is disposed immediately above the side branches of the approximately rectangular loop, when this is in its safety position, to lock the loop in this position.
